UNITED STATES PATENT OFFICE.

ERNEST M. WHITE, OF GLOBE, ARIZONA.

REISSUED

SPLASH SYSTEM OF LUBRICATION.

1,030,148.

Specification of Letters Patent. Patented June 18, 1912.

Application filed January 4, 1912. Serial No. 669,308.

To all whom it may concern:

Be it known that I, ERNEST M. WHITE, a citizen of the United States, residing in Globe, Gila county, Arizona, have invented 5 certain Improvements in Splash Systems of Lubrication, of which the following is a specification.

One object of my invention is to provide 10 a novel construction and arrangement of parts adapted for use in connection with engines, especially of the internal combustion type, whereby the act of adjusting the throttle of the engine shall cause a corresponding adjustment of a lubricant regulating device in order that the amount of 15 lubricant in active circulation shall be varied with and in proportion to the amount of work done by the engine.

Another object of the invention is to provide 20 a novel device particularly adapted for use in connection with a splash system of lubrication and having connection with the throttle of the engine, whereby the adjustment of said throttle to vary the flow of 25 fuel to the engine shall in addition cause a greater or less amount of lubricant to be put into active circulation in order to meet the varied conditions resulting from such 30 throttle adjustment; it being especially desired that the device shall be relatively simple, inexpensive and of such a nature as not easily to get out of order.

These objects and other advantageous 35 ends I secure as hereinafter set forth, reference being had to the accompanying drawings, in which:—

Figure 1, is a vertical section to some extent diagrammatic, illustrating my invention as applied to the crank case of an internal 40 combustion engine; Fig. 2, is a transverse vertical section on the line $a-a$, Fig. 1; and Fig. 3, is an enlarged vertical section further illustrating my invention.

In the above drawings, 1 represents a portion 45 of the fuel-supply device or conduit of an internal combustion engine, in which is mounted a throttle valve having an operating arm 2 and a second arm 3 hereinafter referred to. The crank case 4 of the engine, 50 which, in this instance, is of the four-cylinder type, is provided with partitions forming four transversely extending lubri-

cant containers 5, 6, 7 and 8 lying respectively in and adjacent the planes of rotation of the four connecting rods of the 55 engine. The crank end of each of these rods is provided with an extension 9 designed to enter its particular reservoir, and the bottom of the crank case is so arranged that portions thereof on both sides of each reservoir slope toward or into the same.

The one side of the crank case immediately adjacent each of the reservoirs is provided with inclined gutters 10, and each gutter adjacent a given reservoir is so arranged 65 as to collect a portion of the oil splashed up by the connecting rod extension 9 from said reservoir and to discharge such oil into one of the reservoirs next adjacent to it. In the case of the reservoir 5, the gutter 70 adjacent thereto has the form indicated at 11 and consists of two portions draining to a common point from whence as shown in dotted lines in Fig. 1, the conduit 12, leads, usually outside of the crank case, to a pipe 75 13 which discharges into a storage tank 14. Any suitable form of pump 15 has its intake connected to this tank and its outlet arranged to discharge into the reservoir 8.

As well shown in Fig. 3, this particular 80 reservoir 8 is provided with what may be described as an adjustable weir, i. e., there is in one of its sides an opening 16 having a substantially level bottom edge 17 over which the liquid above a predetermined 85 amount entering the reservoir 8 is free to flow into the storage tank 14. Immediately adjacent said edge, however, I mount an adjustable piece 18 having in the present case the form of an elongated cylindrical segment 90 and mounted on a rod 19 carried in a suitable bearing in the crank case or other supporting structure so as to be rotatable. Said rod is provided with a stuffing box where it passes through the side of the crank 95 case and is provided with an arm 20 connected by a link 21 with the arm 3, which, as before noted, is attached to the throttle valve and to the arm 2 whereby this latter is actuated. The adjustable piece 18, which 100 serves as a valve, is of such proportions and is so placed that when the arm 20 is in the position shown its plane face lies at the level or in the same plane as the overflow

edge 17. Owing to the fact that this plane face of the valve or adjustable weir does not intersect the line about which it is rotatable, a movement of the rod 20 in one direction 5 raises that edge of said valve which is adjacent the reservoir 8 and thus requires the accumulation in said reservoir of a body of lubricant greater than that which would ordinarily be retained.

10 Under operating conditions, the arm 20 is so connected to the arm 2 of the engine throttle valve that when said valve is in a position to cause the engine to operate under normal conditions, the valve or weir 15 18 is in the position shown in Fig. 3. Consequently, the operation of the pump 15 maintains the lubricant in the reservoir 8 at the level shown and the splashing up of, said lubricant by the parts 9 of the connecting rod operating therein, causes a certain part of the oil from this reservoir to flow into the gutters 10 adjacent thereto so that it passes to the reservoir 7. As long as the engine is working under normal conditions, the level of lubricant in this reservoir remains at a very definite height sufficient to cause proper lubrication of the engine parts and at the same time the oil splashed up from this reservoir by the connecting rod is passed by the gutter adjacent thereto to the reservoir 6 and so on. Thus, a predetermined and suitable supply of oil is provided and its level in the reservoir 8 is maintained at a predetermined point, 35 since the surplus supplied by the pump 15 would be immediately discharged into the storage tank 14 over the weir edge 17 and the valve 18. If, now, the throttle valve of the engine be opened in view of an increased 40 load or in order to obtain an increase of the speed, the valve or wier 18 is so turned through the link 21 and the arm 20, as to prevent flow of oil from the reservoir 8 until the amount therein has been increased 45 to such a height as to permit of it overflowing the raised edge of the said valve 18; it being of course understood that the pump 15 is at all times operated at a speed necessary to raise the level of lubricant in this 50 tank in spite of the action of the engine in removing it from the same.

As a consequence of the increased height of lubricant in the reservoir 8, a larger quantity of oil is splashed up by the connecting rod operating therein and this increased amount passes to the succeeding reservoirs—each of which is thus provided with an abnormal amount of oil, so that the engine, as a unit, has in active circulation the greater 60 amount of lubricant required by the increase of load. The oil from the reservoir 5 passes from the trough 11 through the conduit 12 and the pipe 13 back to the storage tank 14.

The return of the throttle to its normal 65 open position likewise causes the adjustable wier to be brought back to the position shown in Fig. 3, thus lowering the level of lubricant in the reservoir 8 and causing a corresponding falling off in the amounts in 70 the other reservoirs.

I claim:

1. A lubricating device consisting of an oil container having an overflow opening; a movable member for taking oil from 75 said container; means for supplying oil to the container; with means for varying the position of the bottom edge of the overflow opening to vary the depth of oil in the container.

2. The combination of an oil reservoir having an overflow opening; a member periodically entering the reservoir for removing oil therefrom; means for supplying oil to the reservoir faster than it is removed 85 therefrom by said member; and means for adjusting the overflow to vary the depth of oil in the reservoir.

3. The combination with the throttle of an engine, of an oil reservoir; a movable 90 member mounted to enter the reservoir for removing oil therefrom; means for supplying oil to the reservoir; and a device for varying the depth of oil in the reservoir operatively connected to the throttle so as 95 to be adjustable therewith.

4. The combination with the throttle of an engine, of an oil reservoir having an overflow opening provided with an adjustable member for varying the depth of oil 100 in said reservoir; means for connecting said member with the engine throttle to cause it to be adjusted with said throttle; and means for supplying oil to the reservoir.

5. The combination of an engine crank case having a series of reservoirs formed to be entered respectively by portions of the engine; means for transmitting to certain reservoirs the oil splashed up 110 from other reservoirs; a storage reservoir connected to an end one of said reservoirs; means for delivering oil from the storage reservoir to the other end reservoir; said last reservoir having an overflow opening 115 discharging into the storage reservoir; and means for adjusting the depth at which the oil in said last reservoir discharges through said overflow opening.

6. The combination of a crank case having a series of oil reservoirs respectively entered by moving parts of the engine; means for delivering oil splashed up from certain of the reservoirs into adjacent reservoirs; a storage reservoir connected to receive oil splashed up from an end one of said reservoirs; means for delivering oil from the storage reservoir to the other end

reservoir; said latter reservoir having an overflow provided with an adjustable structure for varying the depth of oil therein; a throttle for the engine; and means for operatively connecting said throttle with the said adjustable structure.

In testimony whereof, I have signed my

name to this specification, in the presence of two subscribing witnesses.
